UNITED STATES PATENT OFFICE.

CHARLES BAECHLER, OF KANSAS CITY, KANSAS.

RAIL TIE AND FASTENING.

1,027,370.

Specification of Letters Patent. Patented May 21, 1912.

Application filed January 6, 1912. Serial No. 669,819.

To all whom it may concern:

Be it known that I, CHARLES BAECHLER, a citizen of the United States, residing at Kansas City, county of Wyandotte, State of Kansas, have invented certain new and useful Improvements in Rail Ties and Fastenings, of which the following is a specification, reference being had therein to the accompanying drawing.

10 This invention relates to certain new and useful improvements in ties and more particularly to fastening devices therefor, one of the objects being to provide a T-shaped casting of any suitable material which is set 15 within a reinforced tie of any plastic material and adapted to receive and firmly anchor a bolt against any strain to which it may be subjected.

Another object of the invention is to provide 20 a chair-plate adapted to rest upon the flanges of the casting which is provided with means for preventing any horizontal movement of the plate and consequent spreading of the rails.

25 A further object of the invention is to provide a bolt which is so secured within the casting as to permit of its ready insertion and removal and one which will securely lock the clip against all strain to which it 30 may be subjected.

A still further object of the invention is to provide a rail clip which holds the bolt in proper position within the casting.

Another object is to provide a reinforced 35 tie whereby, when the device is assembled, a strong, efficient and durable railroad-tie is formed.

Other and further objects and advantages 40 of the invention will be hereinafter set forth and the novel features thereof defined by the appended claims.

In the drawings—Figure 1 is a plan of the invention showing the rails firmly secured in position; Fig. 2 is a vertical longitudinal section taken on line 2—2 of Fig. 1; Fig. 3 is a vertical transverse section taken on line 3—3 of Fig. 1; Fig. 4 is a perspective view of the chair-plate detached; Fig. 5 is a perspective view of the casting; Fig. 6 is a 50 perspective of a portion of the tie showing the casting arranged therein and the manner of securing the same by the reinforcing members; Fig. 7 is a perspective view of the clip; and Fig. 8 is a perspective view of the bolt.

Like numerals of reference refer to like parts in the several figures of the drawings. Referring to the drawings, 1 indicates a tie of any suitable construction, but is herein shown as of concrete, and 2 a T-shaped casting of any suitable material having the stem 3 which is reduced and extended to provide longitudinal projecting portions 4—4. On either side of the stem of the casting at its lower end and to each side of its center is a laterally projecting lug 5, as clearly shown in Fig. 5, forming a key portion which, together with the longitudinal projecting portions, 4—4, securely anchor the casting within the tie. The flanges 6—6 of the casting 2 are embedded in the tie 1, the upper face of the flanges being flush with the top of the tie, said flanges being provided with transverse shoulders 7—7 at either end and with spaced pins 8 for a purpose later described. Adjacent the ends of the flanges of the casting and extending into the stem thereof are vertical elongated recesses 9—9 which enlarge, adjacent the bottom of the stem, into chambers 10—10, (Fig. 2), for the purpose later described.

Adapted to rest upon the flanges 6—6 of the casting 2 is a chair-plate 11 having recesses 12 in its under face and elongated openings 13—13 corresponding in shape to the recesses 9—9 in the casting and so positioned that when the chair-plate is properly placed upon the flanges of the casting, the openings 13—13 and recesses 9—9 register with one another; while the pins 8 formed on the flanges 6—6 seat within the recesses 12 of the chair-plate and securely hold the same against any horizontal movement. The chair-plate is further provided with square ends 14 which fit against the transverse shoulders 7—7 of the flanges and at either end of the chair-plate is a transverse flange 15 for a purpose later described; while on either side of the transverse center of the upper face of the chair-plate is a transverse groove 16 whereby the plate is lightened and still presents a firm foundation for the base of the rail 17.

Adapted to pass downward through the openings 13 in the chair-plate 11 and into the recesses 9 of the casting 2, are bolts 18 having at their lower ends oval heads 19 which pass into the enlarged chambers 10 of the casting and, when the bolt is turned one-quarter way around, are securely held there-

in. Adjacent the upper end of the bolt, namely that part thereof which when the bolt is in position within the casting, passes through the rail clip 20, is an oval portion 21, as clearly shown, Figs. 2 and 8, the protruding parts of which are at right angles to those of the head 19 of the bolt. The rail clip 20 is provided with an oval slot 22 extending longitudinally of the clip and of the tie when the device is assembled, which enables the oval portion 21 of the bolt to pass into and be retained therein, the rail clip being secured in place by means of a nut 23, that part of the bolt above the oval portion 21 being provided with screw threads for that purpose, a nut-lock washer 24 being used to secure the nut and clip in position with relation to each other. The clip is provided with the usual projecting or rail engaging portion 25, while the other end 26 of the clip is adapted to abut against the transverse flange 15 of the chair-plate 11 to prevent lateral movement thereof and spreading of the rail. It will be seen that my improved device is adapted for use in connection with different weights of rail, it only being necessary to provide different sized clips having longer or shorter body portions and rail engaging portions to accommodate the width of the base of the rail.

As before stated, the tie used in my improved device may be of any suitable construction, having in view the climate and the nature of the roadbed. In order to carry out the policy of efficiency of my invention, I employ a reinforced tie, which consists of a series of twisted wires or bars 27, of any suitable material, spaced apart and running longitudinally of the tie, said longitudinal wires or bars being held in position by means of a series of cross wires 28 spaced at intervals along the tie, (Fig. 6). Two or more of the cross wires abut transversely against the stem of the casting at the angle formed by the longitudinal projection of the stem as shown at 29 (Fig. 2), which materially aids in retaining the casting in position within the tie.

In assembling the parts of my improved device, I first place the chair-plate in position on the flanges of the casting, which is embedded in the tie, and then drop the bolts through the openings in the chair-plate and into the recesses and chambers of the casting; and turn them so as to lock the same; place the rails in position on the chair-plate and insert the clip over the upper end of the bolt so that when the clip is in proper position in regard to the rail, the oval head of the bolt will be secured within the chamber of the casting and when the nut and washer are applied, the device will be securely held against all strain to which it may be subjected.

It will, therefore, be seen that I have pro-

vided a device which is highly desirable, due to its simplicity of construction and the rapidity with which it may be assembled or taken apart, and one which is capable of use with rails of different weights, so that it meets with all present needs of railroad construction.

The side walls of the chambers 10—10, adjacent the bottom of the stem 3 of the casting 2, are formed by the lateral projections 5, said chambers receiving the oval heads 19 of the bolt 18, so that when the bolt is turned one-quarter way around, the projecting portions of the head lie under the upper walls of the chamber so as to retain the bolt within the casting.

It is apparent that some of the details of my invention are capable of use in connection with ties other than those that are formed of plastic material.

What I claim is—

1. A railroad tie having a plastic body, a T-shaped casting embedded therein, the flanges thereof being provided with spaced pins, and a chair-plate resting upon said flanges having recesses therein in which said pins are adapted to seat.

2. A railroad tie having a plastic body, a T-shaped casting embedded therein, the flanges thereof being provided with spaced pins, a chair-plate resting upon said flanges having recesses therein in which said pins are adapted to seat, and means for securing a rail upon said chair-plate.

3. The combination with a tie, of a casting, the upper portion of said casting having transverse shoulders and spaced pins, and a chair-plate fitting between said shoulders and having recesses therein in which said pins seat.

4. The combination with a plastic tie, of a T-shaped casting, the flanges of said casting having transverse shoulders, spaced pins upon the flanges of said casting, a chair-plate fitting between said shoulders and having recesses therein in which said pins seat, and means for securing a rail upon said chair-plate.

5. The combination with a plastic tie, of a T-shaped casting provided with recesses and chambers, the flanges of said casting having transverse shoulders, spaced pins upon said flanges, a chair-plate fitting between said shoulders and having recesses therein in which said pins seat, said chair-plate having elongated openings registering with the recesses in said casting, bolts passing through said openings and secured within said chambers, rail clips embracing said bolts to retain the heads thereof within said chambers, and means for binding the parts together.

6. The combination with a plastic tie, of a T-shaped casting having recesses and chambers, a chair-plate resting upon the flanges of said casting, said chair-plate having

openings registering with the recesses in said casting, transverse flanges upon said chair-plate, rail clips communicating with the openings in said chair-plate, said rail clip 5 abutting against the transverse flanges of said chair-plate, and means for securing said rail clip in position.

7. In a railroad tie, the combination with a plastic body, of a T-shaped casting having 0 recesses and chambers therein, a chair-plate resting upon said casting, elongated openings in said chair-plate registering with said recesses, a bolt having an oval head adapted to pass through said recesses and to be 5 turned within said chambers, a clip having a slot to embrace said bolt, and means for securing said clip in position about said bolt.

8. In a railroad tie, the combination with 0 a plastic body, of a T-shaped casting having recesses and chambers therein, a chair-plate resting upon said casting, said chair-plate having elongated openings registering with said recesses, a bolt having an oval head 5 adapted to pass through said recesses and to be turned within said chambers, said bolt having an oval portion adjacent its upper end at right angles to said oval head, said bolt being screw threaded at its end, a clip 0 having an oval slot to embrace the oval portion of said bolt, a nut for engaging said screw threads and securing said clip in position about said oval portion, and a nut-lock washer for engaging said nut and clip.

5 9. In a railroad tie comprising a body, a casting embedded in said body, said casting being provided with spaced pins, a chair-plate resting upon said casting having recesses in which said pins are adapted to 0 seat, and means for securing a rail upon said chair-plate.

10. In a railroad tie comprising a plastic body, a casting embedded in said body hav-

ing recesses and chambers, spaced pins upon said casting, a chair-plate arranged upon 45 said casting and having recesses therein in which said pins seat, said chair-plate having elongated openings registering with the recesses in said casting, bolts passing through said openings and secured within said chambers, rail clips embracing said bolts to retain the heads thereof within said chambers, and means for binding the parts together.

11. A railroad tie having a plastic body, a casting embedded in said body having recesses and chambers therein, a chair-plate resting upon said casting, said chair-plate having elongated openings registering with said recesses, a bolt having an oval head adapted to pass through said recesses and to 55 be turned within said chambers, a clip having a slot to embrace said bolt, and means for securing said clip in position about said bolt.

12. A railroad tie having a plastic body, 65 a casting embedded in said body having recesses and chambers therein, a chair-plate resting upon said casting, said chair-plate having elongated openings registering with said recesses, a bolt having an oval head 70 adapted to pass through said recesses and to be turned within said chambers, said bolt having an oval portion adjacent its upper end at right angles to said oval head, said bolt being screw threaded at its end, a clip 75 having an oval slot to embrace the oval portion of said bolt, a nut for engaging said screw threads and securing said clip in position about said oval portion, and a nut-lock washer for engaging said nut and clip.

80 In testimony whereof I affix my signature in presence of two witnesses.

CHARLES BAECHLER.
